United States Patent Office.

CHARLES SPEAR, OF NEW YORK, N. Y.

Letters Patent No. 101,174, dated March 22, 1870.

IMPROVEMENT IN SUBMARINE TUNNELS.

The Schedule referred to in these Letters Patent and making part of the same.

To all whom it may concern:

Be it known that I, CHARLES SPEAR, of New York, in the county of New York and State of New York, have invented a new and valuable Improvement in Marine Structures; and I do hereby declare that the following is a full, clear, and exact description of the construction and operation of the same, reference being had to the annexed drawings making a part of this specification and to the letters and figures of reference marked thereon.

Figure 1 of the drawings is a representation of a longitudinal section of my tunnel in plan.

Figure 2 is a transverse vertical section of the same.

My invention relates to submarine tunnels and other works of similar nature, and consists mainly in the construction and novel arrangement thereof, whereby a submarine structure may be formed of frame-work and concrete on land or on the surface of the water, floated to its place of destination, and sunk into position.

The drawings represent my submarine tunnel, consisting of a flattened tube of oval or nearly oval cross-section, built entirely on land or on the surface of the water, in the following manner:

The profile of the river-bed having been taken, the kelson is laid as if for a canal boat, of the requisite length to reach entirely across the bed from bank to bank. My tunnel is, in fact, a boat, and similarly constructed.

A A represent the ribs, to the inner surface of which are fastened the ceiling and flooring a.

The ribs are also covered on the outside with strong planking c.

The spaces between the ribs, and between the ceiling and flooring, and the planking, are filled in with beton, concrete, or a similar composition, z.

The planks are secured both inside and outside by bolts and trenails, exactly as in ship-building, and caulked.

The ends of the tunnels are formed with an upward curve, to correspond with the sudden slope of each river-bank, and of sufficient length that, when the tunnel is sunk into place, they will not be entirely submerged. The entire outside surface of the struc-

ture is coated with concrete, to render it weighty, durable, and waterproof. The tunnel is now floated to its place of destination, and anchored across the river directly over its prepared bed at the bottom thereof.

Suitable guides being driven on each side of the tunnel, the water is let in through openings arranged for the purpose, thereby allowing the tunnel to sink gradually to its position on the river-bottom. It is now fastened down securely to its place, and, the inlet-openings having been closed, the water is pumped out, leaving a dry, serviceable, and water-proof passage under the river from bank to bank.

The tunnel may be permanently secured to its bed by driving, from the inside, rows of spikes or anchoring-screws, e e, having coarse threads, into the soil of the river-bed, arranging them on each side to slant outward as well as downward into the earth.

My invention is applicable to the construction of other marine works. Hollow piers, breakwaters, the foundations of houses, &c., may be built in this manner, floated to their destinations, and sunk into place, thus saving much of the expense of such submarine works incidental to the usual methods of forming them, or putting them together under water.

I am aware that submarine tunnels have been constructed in sections. I do not claim such tunnels; but

What I claim as my invention, and desire to secure by Letters Patent, is—

The floating water-proof tunnel or other marine work herein described, having frame A, concrete covering and filling z, and fastening-screws or anchors e e, when built above water in one entire structure, and arranged to be floated to its destination and sunk into place, as specified.

In testimony that I claim the above, I have hereunto subscribed my name in the presence of two witnesses.

CHARLES SPEAR.
